United States Patent Office

Des. 227,359
Patented June 19, 1973

227,359

CAR-TOP CARRIER

Sidney L. Perry, 5145 Kelvin Ave.,
Los Angeles, Calif.

Original design application May 21, 1968, Ser. No. 12,035,
now Patent No. 214,727, dated July 22, 1969. Divided
and this application June 16, 1969, Ser. No. 19,796

Term of patent 14 years

Int. Cl. D12—09, 16
U.S. Cl. D14—27 C

FIG. 1 is a rear, top and right side perspective view of a car-top carrier, showing my new design;

FIG. 2 is a right side elevation view thereof; the left side, not shown, is a mirror image of the right side;

FIGS. 3 and 4 are respectively rear and front elevation views thereof; and

FIG. 5 is a top plan view thereof.

This is a division of application Ser. No. D. 12,035, filed May 21, 1968, now Patent No. D. 214,727, issued July 22, 1969.

I claim:

The ornamental design for car-top carrier, substantially as shown and described.
